United States Patent Office.

NATHAN LAWRENCE, OF TAUNTON, MASSACHUSETTS, ASSIGNOR TO REED AND BARTON, OF SAME PLACE.

Letters Patent No. 76,639, dated April 14, 1868.

IMPROVED BUTTER-DISH.

The Schedule referred to in these Letters Patent and making part of the same.

TO ALL PERSONS TO WHOM THESE PRESENTS MAY COME:

Be it known that I, NATHAN LAWRENCE, of Taunton, of the county of Bristol, and State of Massachusetts, have made an invention of a new and useful Improvement in Butter-Dishes having rotary covers; and I do hereby declare the same to be fully described in the following specification, and represented in the accompanying drawings, of which—

Figure 1 is a top view of a butter-dish with its cover down, such dish being provided with my improvement.

Figure 2 is a longitudinal section, and

Figure 3 a transverse section of it.

Figure 4 is a transverse section taken through one of the spring-clasps or latches for supporting the boxes or bearings of the journals of the rotary cover.

The butter-dish on which my present invention is an improvement, is described in Letters Patent, No. 71,889, granted December 10, 1867, to Reed and Barton, assignees of myself, the inventor of the subject of such patent.

The boxes of the journals of the cover of the said butter-dish were held in their sockets by means of pins, extending through them and the sockets, and connected to the dish by means of chains.

These pins are very liable to become detached from the vase or dish, and lost. The purpose, therefore, of my present improvement is to avoid the employment of such pins, and to use in lieu of them spring-latches, to support the box or bearing, clasp it on its opposite sides, and latch upon and hold it down or in place under ordinary circumstances. These latches admit of the easy removal of the boxes from them, but hold them with more than sufficient tenacity to enable the whole dish, with whatever it may contain, to be readily lifted by its handles when the cover is up.

In the drawings, A denotes the vase, having a semi-ellipsoidal body, *a*, containing a semi-ellipsoidal concentric cup, B, the two being connected at their edges by a portion, *b*, of an annulus. A strainer, *s*, for supporting the butter, is placed within the cup B. The dish has four feet, *c*, projecting down from it, and it also has two furcated brackets, *m m*, extended from it, as represented, such brackets being for support of a knife to be used for cutting the butter.

The rotary cover, C, of the dish or vase is provided with two journals, *d d*, extending in opposite directions from it, and in the longer axis of it. Each of the journals terminates in a cross-head or handle, *e*, and runs through a box or bearing, *f*, which entirely encompasses the journal.

Each of these bearings, when in place, is supported between and by two spring-latches, *g g*, projecting from an ear, *h*, and formed in manner as represented in figs. 1 and 4. The latches, while holding the bearings in place with sufficient friction under ordinary circumstances, (that is, the covering and uncovering the vase, or lifting it by the handles of the cover and transferring it from place to place when the cover is up or out of the vase,) should be capable of yielding so as to enable the bearings to be raised from between them, (the said latches,) in order to allow of the removal of the cover from the vase for the purpose of cleaning either or both.

A friction-spring, *l*, placed in a chamber, made in the cross-head of the journal, bears against the end of the box or bearing, and, by so doing, serves to retain the cover in any position, whether it be either wholly or partially over the vase.

I do not claim, for supporting and holding the cover, journal-boxes in place, inflexible sockets and pins to go through them and the boxes, such being as represented and described in my patent as hereinbefore mentioned; but

I claim the combination and arrangement of the spring-latches *g g* with the vase, and for the purpose of receiving and holding the bearings or boxes of the journals of the cover, and admitting of their removal, in manner substantially as specified.

NATHAN LAWRENCE.
